UNITED STATES PATENT OFFICE.

ALBERT J. LINDEMANN, OF MILWAUKEE, WISCONSIN, ASSIGNOR TO A. J. LINDEMANN & HOVERSON CO., OF MILWAUKEE, WISCONSIN, A CORPORATION OF WISCONSIN.

OIL-VAPOR BURNER.

SPECIFICATION forming part of Letters Patent No. 738,463, dated September 8, 1903.

Application filed December 18, 1902. Serial No. 135,699. (No model.)

To all whom it may concern:

Be it known that I, ALBERT J. LINDEMANN, a citizen of the United States, residing at Milwaukee, in the county of Milwaukee and State of Wisconsin, have invented certain new and useful Improvements in Oil-Vapor Burners, of which the following is a specification, reference being had to the accompanying drawings, forming a part thereof.

This invention relates to self-generating oil-vapor burners specially designed for the more volatile hydrocarbons, such as gasoline. Its main object is to simplify and improve the construction and operation of this class of burners, and particularly to completely vaporize the oil before it reaches the jet-nozzle with the axis of the air-mixing tube in assembling the parts of the burner and to avoid as far as practicable threaded joints in the construction of the burner.

It consists in certain novel features of construction and in the arrangement and combinations of parts, as hereinafter particularly described, and pointed out in the claims.

In the accompanying drawings like letters designate the same parts in the several figures.

Figure 1 is a view, partly in side elevation and partly in vertical medial section, of a burner embodying my improvements. Fig. 2 is an inverted plan view of the base-plate and a horizontal section on the line 2 2, Fig. 1; and Fig. 3 is a similar section on the line 3 3, Fig. 1.

a is a substantially circular base-plate formed on the upper side with a circular depression in which is loosely fitted the perforated cap *b* in the usual or any suitable manner.

c is a vertical air-mixing tube fitted and held in a central flanged opening in the base-plate and projecting upwardly through the same in the usual way.

On one side the plate *a* is formed with an ear or extension *d*, having a circular hole through it and a recessed seat *e* of angular or irregular shape in the under side around said hole.

f is a hollow vaporizing-head having a circular threaded portion fitted to pass through

and extend upwardly above the hole in said base-plate and also having a shoulder below said circular portion fitted in the seat *e*. This head is secured in the base-plate above which it projects, as shown in Fig. 1, by a nut *g*. 55

h is a vapor-jet nozzle connected with the head *f* by an angular pipe or passage *i*, which is formed integrally with said nozzle and head. The position of the nozzle relative to the base-plate *a* is thus determined by the engagement of the shoulder or enlargement of the head *f* with the recessed seat *e* in said base-plate, and the nozzle is thus brought into and securely held in exact axial alinement with the air-mixing tube *c* when the parts of the 65 burner are assembled as shown in Fig. 1. The nozzle *h* is provided, as usual, with a valve *j* for opening and closing it and for admitting oil into a cup *k* on the lower part of the nozzle for heating the burner preparatory 70 to lighting it. The vapor-feed tube *i* is also provided in the usual way with a regulating-valve *l*.

m is a vertically-arranged oil-supply pipe threaded at its upper end in the lower part 75 of the head *f* and communicating above the base-plate *a* through a passage *n* in said head with the passage in the pipe *i*.

By this construction and arrangement of the oil and vapor pipes and the vaporizing-head 80 *f* the oil supplied through the pipe *m* is compelled to pass into the upper part of the head *f*, which is exposed directly to the flame of the burner and is highly heated thereby. After the burner has been heated the oil in its 85 passage thereto is thus completely vaporized before it enters the pipe *i*. The pipe *m* is preferably provided with a filter or strainer *o*, of loose cotton or other suitable material, held therein between perforated caps *p*, inserted in the ends of said pipe for the purpose of removing any impurities contained in the oil before it enters the vaporizing-head. 90

Except as above explained the operation of the burner is like or similar to that of burners of this class. To start the burner, both the valves *k* and *l* are opened and oil is allowed to overflow the nozzle *h* into the cup *k*, in which it is burned till the parts of the 95 burner are heated sufficiently to vaporize the 100

oil before it issues from said nozzle. When this occurs, the jet of oil-vapor issuing from the nozzle *h* and regulated in the usual way by the valve *l* entrains air with it upwardly 5 through the mixing-tube *c* into the cap *b*, from the perforations in which the inflammable mixture of oil-vapor and air issues and burns with a blue flame. The flame from the lower row of holes in the cap impinges against 10 the vaporizing-head *f*, keeping the same hot and completely vaporizing the oil as it is supplied thereto through the pipe *m*.

Various changes in minor details of construction and arrangement of parts may be 15 made within the spirit and intended scope of the invention.

I claim—

1. In an oil-vapor burner the combination of a base-plate provided with a vertical air-mixing tube and with a perforated cap, a head 20 extending above said plate and exposed to the flame of the burner, said head having a vaporizing chamber or passage also extending above said plate, and a jet-nozzle arranged 25 below and in alinement with said mixing-tube and connected by a pipe or passage with said head, substantially as described.

2. In an oil-vapor burner the combination of a base-plate having a vertical air-mixing 30 tube and an opening on one side of said tube, an externally threaded and shouldered vaporizing-head fitted in said opening and secured therein by a nut and a jet-nozzle integrally connected with said head by a pipe 35 or passage and held thereby in alinement with the axis of said air-mixing tube, and an oil-supply pipe connected with said head and

communicating with the aforesaid pipe or passage above said base-plate, substantially as described.

3. In an oil-vapor burner the combination of a base-plate having an air-mixing tube perpendicular thereto and an opening and recessed seat at one side of said tube, a hollow vaporizing-head fitted in said opening and seat to project above said plate and secured therein by a nut threaded on said head, a jet-nozzle formed integrally with said head and held thereby in axial alinement with said air-mixing tube, and an oil-supply pipe threaded 40 in said head below said plate and communicating above said plate with the passage leading to said nozzle, substantially as described.

4. In an oil-vapor burner the combination of a base-plate provided with a perforated cap 45 and with a vertical air-mixing tube and having an opening through it on one side of the cap-seat, a hollow vaporizing-head secured in said plate and projecting above it adjacent to one or more openings in the cap, a jet-nozzle 50 arranged in alinement with the axis of said air-mixing tube and connected by a passage with said head above the base-plate and an oil-supply pipe located below said base-plate and connected above it by a passage 55 with the passage leading to said nozzle, substantially as described.

In witness whereof I hereto affix my signature in presence of two witnesses.

ALBERT J. LINDEMANN.
